UNITED STATES PATENT OFFICE.

ALEXANDER HOSTETTLER, OF COLUMBUS, OHIO.

PASTEURIZING APPARATUS.

1,367,517.

Specification of Letters Patent.

Patented Feb. 1, 1921.

Application filed September 6, 1919. Serial No. 322,007.

To all whom it may concern:

Be it known that I, ALEXANDER HOSTETTLER, a citizen of the United States, residing at Columbus, in the county of Franklin 5 and State of Ohio, have invented a certain new and useful Improvement in Pasteurizing Apparatus, of which the following is a specification.

The object of this invention generally and 10 principally is an improved apparatus for pasteurizing beer, near-beer and other beverages generating or containing gas, in such a way as to accomplish that result economically and effectively and without altering 15 the palatability of the liquid treated. A special object of the invention is to utilize the heat of the pasteurized liquid to preliminarily heat the cold untreated liquid and conversely to promote the cooling of 20 the heated liquid with the cold untreated liquid thereby saving fuel and the necessity of using a circulated or flowing cooling medium for the treated liquid. Another object is an improved form of pasteurizing 25 vessel.

The invention is embodied in the example herein shown and described, the features of novelty being finally claimed.

In the accompanying drawing the view 30 illustrates partially in elevation and partially in section an apparatus embodying my invention.

In said view 1 designates a heater for the liquid of ordinary form and 2 a cooler also 35 of ordinary form. This heater can be provided with a steam inlet as at 1^a.

Arranged vertically between the heater and cooler is the pasteurizing vessel or cylinder 3, preferably porcelain lined and of 40 a construction adapted to conserve the heat of the liquid to be pasteurized. A pipe 4 leading from the upper end of the heater discharges into the upper end of the cylinder 3. The cylinder 3 contains a stationary 45 screw 5 extending substantially the entire length thereof, said screw fitting within the vessel or lying at its edges close to the wall of the cylinder and being of slow pitch as shown so as to provide a long inclined 50 passage for the liquid through the cylinder thereby prolonging or retarding its flow and preventing much mixing thereof.

6 designates a large inclosed tank which may contain water or other suitable material and shown as having a supply inlet 7 and draining outlet 7^a. Within said tank

are two coiled pipes 8 and 9 having their coils alternating. As compared with the tank the coils are made small so as not to extensively modify the temperature of the 60 water in the tank. Where beer or near-beer or other liquid that should be kept cold is to be treated the coil of the lower pipe 8 is extended as shown at 8^a toward a cellar where a pump 10 is installed to impel 65 the beer through the coil 8 and through an extension 8^b of the upper coil to the lower portion of the heater 1.

Connected with the lower end of the cylinder 3 is a pipe 11 leading to a pump 12, 70 the outlet of which is connected with an extension 9^a of the pipe 9 so that the hot liquid from the pasteurizing vessel 3 can be pumped through said pipe 9 and thence discharge through an extension 9^b of the 75 uppermost coil of said pipe 9. The pipe 9^b is connected with the final cooler 2.

Thermometers 13, 14 and 15 upon the heater, pasteurizing vessel and cooler, respectively, are provided for indicating the 80 temperature of the liquid in those parts, so that the operation for successful pasteurizing can be conducted accordingly. The temperature for pasteurization and the time of application of temperature are well understood. The temperature is obtained by 85 regulating the heating steam and the time necessary by regulating the flow.

Suitable valves, as shown, are provided for controlling or cutting off the flow of 90 liquid through the vessels and coils and of the fuel to the burner of the heater as may be desired or necessary.

Beer or near-beer in breweries is ordinarily kept in the cellar at near the freezing 95 point. In the practice of my invention, in the treatment of these beverages, therefore, the cold liquid is first passed through the coil 8 and warmed or heated by the passage of the liquid from the pasteurizing vessel 100 through the coil 9. The alternation of the coils 8 and 9, that is with the successive coils 9 below the coils 8 and the placing of them in close proximity to each other greatly promotes the warming of the liquid from the 105 cellar and the cooling of the liquid from the pasteurizer. This effects a large economy of fuel at the heater and a saving of power in pumping water for cooling purposes. The water in the large tanks 6 need seldom be 110 renewed but if a particular temperature thereof for special purposes should be needed

a flow through the tank at the temperature required can be had by using the inlet and outlet thereof. Suitable means can be employed where desirable for introducing and 5 maintaining a suitable gas pressure in the pasteurizing vessel to prevent the escape of gas from those liquids containing gas, said means being indicated at the upper end of the pasteurizing vessel where 16 designates 10 the gas inlet pipe and 17 a gage for observing the pressure.

With this apparatus it is obvious that the pasteurizing process can be carried on continuously from the chip cask to the racking 15 machine.

The forms of the parts can be changed without departing from the gist of the invention as claimed.

What I claim is:

20 1. In a pasteurizing apparatus, the combination of a heater for the liquid to be pasteurized, an upright pasteurizing vessel having a chamber with a fixed screw of slow pitch fitting therein to form an extended 25 passage, a conductor for the heated liquid discharging into the upper end of the chamber, said chamber provided with an exit for the pasteurized liquid at its lower end.

2. In pasteurizing apparatus the combination of a heater, a pasteurizing vessel, a 30

tank, and a pair of distinct coils of pipe in said tank, one coil connected with the heater for the passage of cold liquid to the heater and the other coil for the passage of hot pasteurized liquid from the pasteurizing vessel, 35 said pipes having their coils alternating with each other and in proximity to each other whereby the cold liquid in one coil is warmed by the hot liquid in the other.

3. In pasteurizing apparatus, the combination of a heater, a pasteurizing vessel, a tank and a pair of distinct coils of pipe in said tank, one coil connected with the heater for the passage of cold liquid to the heater and the other coil for the passage of hot pasteurized liquid from the pasteurizing vessel, 40 said pipes having their coils in proximity to each other whereby the cold liquid in one coil is warmed by the hot liquid in the other.

4. In a pasteurizing apparatus, the combination of a heater for the liquid to be pasteurized, an upright pasteurizing vessel having a cylindrical chamber with a fixed screw of slow pitch fitting therein to form an extended passage, a conductor for the 45 heated liquid discharging into the upper end of the cylindrical chamber, said chamber provided with an exit for the pasteurized liquid at its lower end.

ALEXANDER HOSTETTLER.
